VACUUM CLEANER

Jan Carl Olason, Stockholm, Sweden, assignor to
Electrolux Corporation, Dover, Del., a corpora-
tion of Delaware

Application July 6, 1934, Serial No. 734,007
In Germany July 19, 1933

14 Claims. (Cl. 230—115)

My invention relates to vacuum cleaners and the method of operation thereof.

The air flow producing device of a vacuum cleaner, during the ordinary use of the cleaner, is called upon to circulate varying quantities of air. These variations in quantity may be caused by several factors acting either singly or in combination. For instance, if the cleaning tool or nozzle is attached directly to the cleaner unit there is less resistance offered to the flow of air than if the nozzle is connected to the unit by an intervening length of hose, and consequently, other factors being the same, the quantity of air circulated in the first case is greater than in the second. Likewise, a large nozzle offers less resistance to the flow of air than does a small one. Also, the nature of the surface being cleaned has an effect on the resistance. A hardwood floor, for instance, has less sealing effect on the cleaning nozzle, and hence offers less resistance to air flow, than does a heavy carpet. A loosely woven rug has less sealing effect than does a rug with a close weave. Whenever the resistance to the flow of air is small, the reduction in pressure caused by the fan or other air flow producing means need be but comparatively small, while when the resistance is large the reduction should be comparatively great in order to draw the air in against the high resistance.

One of the objects of the invention is to provide an air flow producing device which will produce a large air flow with a small reduction of pressure and, when the air flow is reduced, will cause a large drop in pressure while operating with high efficiency under both of these conditions.

Further objects and advantages of my invention will be apparent from the following description considered in connection with the accompanying drawing which forms a part of this specification and of which:

Fig. 1 is a cross sectional view of a vacuum cleaner including one embodiment of my invention;

Fig. 2 is a cross sectional view of a portion of the vacuum cleaner including another embodiment of my invention; and

Fig. 3 is a performance curve of a vacuum cleaner including either of the embodiments.

Reference character 10 designates a preferably cylindrical air-tight casing. A ring 11 is secured to one end of casing 10. A bell-shaped member 12 is adapted to be clamped to ring 11 by means of suitable spring clips 13, and is provided with a central threaded inlet opening 14. A coupling member 15 is adapted to be screwed into opening

16 and also to receive one end of a hose 16. The other end of the hose may be connected to a cleaning nozzle 17. A dust bag 18, made of material which is pervious with respect to air but prevents the passage therethrough of dust, has its open end secured to a ring 19, which is formed with an outwardly extending flange 20. Flange 20 is provided with a packing member of rubber or other suitable material, and is clamped between ring 11 and member 12.

The rear end of casing 10 is provided with a ring 21 to which is secured by means of bolts 22 a motor supporting ring 23. A motor 24 is suitably supported within ring 23, as by means of lugs 25 on the ring which engage springs 26 supported in lugs 27 formed on the motor housing. The motor is thus resiliently supported.

A member 28 having a perforated wall 28a encloses the rear end of motor 24 and is secured to ring 23 by bolts 28b. A cap member 29 fits over the cylindrical part of member 28 and may be removably held in place by spring clips similar to spring clips 13. Cap 29 is provided with an outlet opening 30, in which are arranged inclined vanes 31 for directing the air discharged therethrough upwardly and away from the surface on which the cleaner is supported. Arranged between member 28 and the outlet 30 in cap 29 is a filter 32 which fits within cap 29.

A handle 33 for carrying the cleaner is secured to the upper part thereof. One end of the handle is fastened within a standard 34 which also serves to house an electric switch 35 and contact members 36. The cleaner unit is supported horizontally above the horizontal surface by means of a pair of runners 37 which are secured to rings 11 and 21 at opposite ends of the casing 10.

A fan rotor 38 is mounted on the shaft of motor 24, so as to rotate therewith. Rotor 38 includes a circular disc 38a secured to the motor shaft. A plurality of curved blades 38b are carried by disc 38a, the right hand edges, as viewed in Fig. 1, of the blades being secured to the disc. The opposite edges of the blades are secured to a disc 38c formed with a central circular opening. A fan housing comprising a cylindrical portion 39 and an end wall 40 is supported on ring 23 and encloses the rotor 38. Wall 40 is formed with a central opening 41 which, under certain conditions, is closed by a valve member 42. Valve member 42 comprises a circular disc supported by a hub 43 which is slidably mounted on a pin 44. The pin 44 is rigidly secured to an arm 45 which extends across opening 41. A spring 46 surrounds pin 44 and has one end bearing against

hub 48 and the other end against a head 47 on the pin. Spring 46 therefore tends to force the valve member 42 to a closed position. Secured within the forward part of the fan housing is an inner 5 housing 48 which forms an annular passage 49 between itself and the fan housing. The forward end of inner housing 48 is supported by end wall 40, while the other end of the housing is provided with a wall 50 having a central opening 51 there- 10 through. Opening 51 constitutes an inlet for the fan rotor 38.

Inner housing 48 is provided with one or more 15 openings in which are secured suction inducing nozzles 52 each having a central passageway 52a formed in the shape of a Venturi tube. Nozzles 52 are preferably arranged so as to have their inner ends directed toward the fan inlet opening 51. End wall 40 is provided with openings in alignment with nozzles 52, into which open- 20 ings are secured induced suction nozzles 53, the inner ends of which terminate within the most constricted part of the Venturi shaped passages 52a in nozzles 52. The outer diameter of the inner ends of nozzles 52 is slightly less than 25 the diameter of said constricted portions, whereby annular passages of small cross sectional area are formed therebetween. The nozzles 52 communicate with the annular passage 49, which in turn communicates with the space within the 30 fan housing adjacent to the outer periphery of the rotor 38.

The operation of the above described vacuum 35 cleaner is as follows: Rotation of rotor 38 by means of motor 24 causes the rotor to draw air from within inner housing 48 through opening 51 and to eject it at the periphery of the rotor. This immediately reduces the pressure within inner housing 48 and consequently air is drawn from within casing 10 around the dust bag 40 through the induced suction nozzles 53. If, for any of the aforesaid reasons, the resistance to air flow through the cleaning nozzle 17 is low, air will pass through the nozzle and hose 16 and through the dust bag 18 in such quantities 45 that it cannot pass through the induced suction nozzles 53 fast enough to balance the reduced pressure within inner housing 48. Consequently, the pressure on the left hand side, as viewed in Fig. 1, of valve member 42, is greater than that 50 on the other side, and the valve member is opened against the action of spring 46. When the valve member is opened, the pressure difference on either side of end wall 40 is reduced, but the dynamic force of the air stream passing 55 through opening 41 maintains the valve open. Consequently, most of the air passes through the large opening 41 and only a small quantity passes through induced suction nozzles 53.

The air discharged from the periphery of 60 rotor 38 passes chiefly to the right, as viewed in Fig. 1, around motor 24, through the openings in wall 28a of member 28, through the filter 32 and is discharged through outlet 30. Under these conditions there is a comparatively large 65 volume of air available for the fan to circulate and the fan is designed to operate efficiently under these conditions.

If the cleaning nozzle 17 is now placed in contact with a rug or the like, or if any other conditions obtain tending to introduce comparatively 70 high resistance into the path of air flow into the cleaner unit, the volume of air drawn into the cleaner unit is correspondingly reduced. This smaller quantity of air does not possess enough 75 dynamic force to maintain the valve member 42

open against the action of spring 46 and the valve member closes. Rotor 38 now produces a lower pressure within inner housing 48 than it was able to maintain with valve member 42 open and air passes from the region of higher than 5 atmospheric pressure at the periphery of the rotor through annular passageway 49 and through suction inducing nozzles 52 to the region of this low pressure within housing 48. In passing through the constricted portions of nozzles 52 10 this air attains a high velocity which produces a strong suction effect on the induced suction nozzles 53, whereby air is drawn through nozzles 53 from the space around the dust bag. Nozzles 52 and 53 form jet pumps or ejectors operated 15 by air discharged from the rotor and, when valve member 42 is closed, produce a lower pressure in the space around the dust bag than the fan maintains within housing 48. This lower pressure is very desirable in order to cause flow of 20 air into the cleaning nozzle 17 against the high resistance offered by the rug or the like.

The air supplied to nozzles 52 from the discharge of the rotor is recirculated through the 25 rotor and makes up for the small volume of air drawn in through the nozzle 17 and hence the rotor has about the same volume of air to handle that it had with valve member 42 open. Inasmuch as the rotor is designed to handle this amount of air, it operates more efficiently than it 30 would with smaller quantities. The air discharged from the rotor and not recirculated passes through the outlet 30 in the same manner as previously described.

It will be noted that the air recirculated, during 35 periods of small air flow through the cleaning nozzle 17, to make up a sufficient quantity for efficient operation of the rotor, is gainfully employed to operate the jet pumps to produce a higher degree of vacuum. This higher vacuum 40 is very desirable in order to draw air into the cleaning nozzle against the high resistance to flow offered by the rug or similar article being cleaned, by a hose, or by a small nozzle. During 45 periods of large air flow through cleaning nozzle 17, the pressure is not so low in housing 48 due to the fact that valve member 42 is open, and consequently there is not a large enough pressure drop through the suction inducing nozzles 52 to cause the recirculation of an undesirably 50 large quantity of air.

Under intermediate conditions of resistance to air flow, valve 42 may be partially closed, thus rendering the jet pumps or ejectors partially 55 effective.

Fig. 3 shows two curves obtained by plotting the quantity of air flow against the vacuum produced. Curve a is that obtained with a vacuum cleaner like that shown in Fig. 1, but without the jet pumps. It will be seen that, as the quantity 60 of air flow is reduced, the vacuum rises at a comparatively small rate and never reaches a very high value, but at a low vacuum a large volume of air may be circulated. Curve b, on the other hand, is that obtained with a vacuum cleaner of 65 the type shown in Fig. 1, but with the valve member 42 permanently closed. This curve indicates that there is a very rapid increase in the degree of vacuum produced as the quantity of air flow is reduced, but that the quantity of air which such a device would be capable of circulating, even at a very small vacuum, is not large. A high degree of vacuum is desirable when there is a high resistance to the flow of air in order to draw air into the cleaner unit against this comparatively 70 75

high resistance, and hence the performance shown by curve *b* is desirable. On the other hand, a large quantity of air flow is desirable when the nozzle is being used to clean hardwood floors, or whenever the resistance is low, as the large quantity of air drawn into the nozzle picks up more dust than would a smaller quantity and therefore, under these conditions, the performance shown by curve *a* is preferable. Consequently, the 5 spring 46 acting on the valve member 42 is so designed as to close the valve member at the point *c* where the curves *a* and *b* cross. Hence, the curve representing the actual performance of the vacuum cleaner shown in Fig. 1 comprises the parts 10 of the curves *a* and *b* shown in full lines. This 15 gives the most efficient operation for the cleaner under all conditions.

The vacuum cleaner shown in Fig. 2 operates on the same principle as that shown in Fig. 1, but it 20 embodies several structural differences. The shaft of motor 24 is provided with a fan rotor 60, which is similar to rotor 38 shown in Fig. 1, having a disc 60a, curved blades 60b and a disc 60c, but disc 60c is provided with a conical flange 25 61 surrounding the inlet opening therein. Rotor 60 is mounted within a fan housing 62. The central part of the forward wall 63 of the housing is formed as an induced suction nozzle 64. Plate 30 members 65 support a valve housing 66, the forward wall 67 of which is formed with a plurality of openings 68 arranged in a circle about the center thereof. A pin 69 is rigidly secured to the center of wall 67 and slidably mounted thereon is a hub 70, which carries a spider 71. Spider 71 35 carries an annular valve member 72, which serves to close openings 68. A spring 73 is arranged around pin 69 with one end bearing against hub 70 and the other end against a head 74 secured to the pin. Spring 73 tends to maintain the valve member 72 in closed position. The rear wall 75 of valve housing 66 is formed with a cylindrical portion 76 which extends within the induced suction nozzle 64. Supported within the fan housing 62 by means of plate members 77 is a partition 78, 40 the central part of which is formed as a suction inducing nozzle 79 having a Venturi shaped passage 79a therethrough, and the outer-periphery of which is spaced inwardly from the cylindrical portion of the fan housing. Induced suction 45 nozzle 64 extends into suction inducing nozzle 79. The conical portion 61 of the rotor disc 60c extends into the annular space formed between nozzle 79 and the remainder of partition 78, as is clearly shown in Fig. 3.

The operation of this embodiment is as follows: If the cleaning nozzle 77 is in contact with a 50 surface which offers but small resistance to the flow of air, or if other conditions exist which result in low resistance, the large volume of air 55 drawn in has sufficient dynamic force to maintain the valve member 72 open against the force of spring 73. Consequently, most of the air passes through openings 68 in the valve housing 66 and through the cylindrical portion 76 to the central 60 inlet of the rotor 60. The rotor discharges the air at its periphery and most of this air passes to the right, as shown in Fig. 2, to the outlet of the cleaner.

If the resistance to flow of air into the cleaning nozzle 77 is increased sufficiently, the small 65 quantity of air drawn in does not have enough dynamic force to maintain the valve member 72 open and the air passes between walls 63 and 75 to the induced suction nozzle 64. The high velocity jet produced by the recirculated air passing

through suction inducing nozzle 79 causes air to be drawn through nozzle 64, thereby producing a higher vacuum within casing 10 around the dust bag than the rotor alone is able to maintain. At the same time, sufficient air is recirculated so that 5 the fan will operate efficiently.

In the embodiment shown in Fig. 2 the induced suction nozzle 64 corresponds to the nozzles 53 shown in Fig. 1. Likewise, the suction inducing nozzle 79 in Fig. 2 corresponds to nozzles 52 in the 10 first embodiment.

The performance of the second embodiment is similar to that of the first, and hence the curves shown in Fig. 3 apply to the second embodiment in the same manner as previously described in 15 connection with the first embodiment.

In the foregoing description and in the claims the expression "high vacuum" or "high degree of vacuum" means a low absolute pressure.

While I have shown and described two more or less specific embodiments of my invention, it is to be understood that this has been done for purposes of illustration only and that they are not intended to limit the scope of my invention, which is to be determined only by the appended 25 claims viewed in the light of the prior art.

What I claim is:

1. In a vacuum cleaner having an inlet offering varying resistance to flow of air therethrough, a plurality of suction producing means for inducing flow of air through said inlet, one of said means being a fan and means for increasing the suction effect of the other suction producing means in response to a decrease in the quantity of air flowing through said inlet caused by an 30 increase in resistance offered by the inlet.

2. In a vacuum cleaner having an inlet offering varying resistance to flow of air therethrough, a plurality of suction producing means for inducing flow of air through said inlet including a 40 fan and an ejector, and means for increasing the effect of the ejector in response to a decrease in the quantity of air flowing through said inlet resulting from an increase in resistance offered by the inlet.

3. In a vacuum cleaner having an inlet, vacuum producing means for causing flow of air therethrough, said means having a suction side in communication with said inlet and a discharge side, means for recirculating air from said 50 discharge side to said suction side, and means operative in response to reduction in the flow of air through said inlet to an amount insufficient for efficient operation of said vacuum producing means to cause flow through the recirculating 55 means.

4. In a vacuum cleaner having an inlet, vacuum producing means for causing flow of air therethrough, means providing parallel paths for the flow of air from said inlet to said vacuum 60 producing means, closure means in one of said paths arranged so as to be maintained open by the dynamic force produced by the flow of a comparatively large quantity of air and a jet pump for increasing the flow of air through the 65 other of said paths operable by the closing of said closure means.

5. In a vacuum cleaner having an inlet, vacuum producing means for causing flow of air therethrough, means provided parallel paths for 70 the flow of air from said inlet to said vacuum producing means, closure means in one of said paths arranged so as to be maintained open by the dynamic force produced by the flow of a comparatively large quantity of air, and means 75

for increasing the flow of air through the other of said paths, said last mentioned means being operable in response to the closing of said closure means upon a reduction in the quantity of air.

5 6. In a vacuum cleaner having an inlet, vacuum producing means for causing flow of air therethrough, means providing parallel paths for the flow of air from said inlet to said vacuum producing means, movable means in one of said 10 paths responsive to variations in the dynamic force of said air flow, and means for increasing the flow of air through the other of said paths, said last mentioned means being operable in response to movement of said movable means.

15 7. In a vacuum cleaner having an inlet offering varying resistances to the flow of air therethrough, a rotor for inducing flow of air therethrough, an ejector, and means operable under conditions of low resistance to admit large 20 quantities of air directly to said rotor and operable under conditions of high resistance to cause the air to pass through said ejector before being admitted to said rotor so as to increase the vacuum produced.

25 8. In a vacuum cleaner having an inlet offering varying resistances to the flow of air therethrough, a rotor for inducing flow of air therethrough, an ejector between said inlet and said rotor, means for supplying air discharged from 30 said rotor as motive fluid for said ejector, and means operable under conditions of low resistance to admit large quantities of air directly to said rotor without passing through said ejector and operable under conditions of high resistance to 35 prevent flow of air directly to said rotor and to increase the effectiveness of said ejector.

9. In a vacuum cleaner having an inlet, a rotor for inducing flow of air therethrough, means forming a chamber communicating with the inlet of said rotor, an inlet valve for said chamber 40 including a spring pressed valve member, and a jet pump discharging into said chamber, said jet pump having a suction inlet communicating with the first-mentioned inlet.

45 10. In a vacuum cleaner having an inlet, a rotor for inducing flow of air therethrough, means forming a chamber communicating with the inlet of said rotor, an inlet valve for said chamber including a spring pressed valve member arranged to be maintained open by the dynamic force of a large volume of air flow, an ejector discharging into said chamber, said ejector having a suction inlet communicating with the first-mentioned inlet, and means for supplying motive fluid to said ejector from the discharge of said rotor.

11. In a vacuum cleaner, a casing having an inlet opening, a fan rotor in said casing, a fan housing around said rotor, an inner housing 60 within said fan housing forming a chamber communicating with the inlet of said rotor, a spring pressed inlet valve for said chamber, and a jet pump including a suction inducing nozzle extending through the wall of said inner

housing and having a motive fluid inlet communicating with the space between said housings, said space communicating with the discharge of said rotor, and an induced suction nozzle extending through the wall of said fan 5 housing and terminating within said suction inducing nozzle and having an inlet in communication with the inlet opening of said casing.

12. In a vacuum cleaner, a casing having an inlet opening, a fan rotor in said casing, a fan 10 housing around said rotor, an inner housing within said fan housing forming a chamber communicating with the inlet of said rotor, a spring pressed inlet valve for said chamber, and a jet pump including a suction inducing nozzle 15 extending through the wall of said inner housing and having a motive fluid inlet communicating with the space between said housings, said space communicating with the discharge of said rotor, and an induced suction nozzle extending through the wall of said fan housing and terminating within said suction inducing nozzle and having an inlet in communication with the inlet of said casing, the spring of said inlet valve having strength sufficient to maintain said valve closed 20 under conditions of comparatively small air flow while permitting it to be maintained open by the dynamic force of a comparatively large volume of air flow.

13. In a vacuum cleaner, a casing having an 30 inlet, a fan rotor in said casing, a fan housing around said rotor, said housing having an inlet formed as an induced suction nozzle, a partition within said housing having a central opening formed as a suction inducing nozzle, said partition forming with said housing a passage communicating with the discharge of said rotor and with said suction inducing nozzle, said induced suction nozzle extending within said suction inducing nozzle, means forming a chamber having 40 an outlet extending within said nozzles, and a spring pressed inlet valve for preventing flow of air into said chamber.

14. In a vacuum cleaner, a casing having an inlet, a fan rotor in said casing, a fan housing 45 around said rotor, said housing having an inlet formed as an induced suction nozzle, a partition within said housing having a central opening formed as a suction inducing nozzle, said partition forming with said housing a passage communicating with the discharge of said rotor and with said suction inducing nozzle, said induced suction nozzle extending within said suction inducing nozzle, means forming a chamber having an outlet extending within said nozzles, and a 50 spring pressed inlet valve for preventing flow of air into said chamber, the spring of said inlet valve having strength sufficient to maintain said valve closed under conditions of comparatively small air flow while permitting it to be maintained open by the dynamic force of a comparatively large volume of air flow.

JAN CARL CLASON.
